UNITED STATES PATENT OFFICE.

JOSEPH SHERMAN, OF BRISTOL, PENNSYLVANIA.

PORTABLE GAME APPARATUS FOR POOL AND BILLIARDS.

SPECIFICATION forming part of Letters Patent No. 244,324, dated July 12, 1881.

Application filed February 4, 1881. (No model.)

To all whom it may concern:

Be it known that I, JOSEPH SHERMAN, a citizen of the United States, residing in Bristol, Bucks county, Pennsylvania, have invented 5 a Portable Game Apparatus for Pool and Billiards, of which the following is a specification.

The object of my invention is to construct a cheap, portable, and effective apparatus for 10 playing the game of pool or billiards, the main features of the invention being the pivoting of the table to the frame of a lounge or sofa, and the construction of the table in such a manner that it can be produced at so cheap a rate as 15 to warrant its use in the making of such a combined article of furniture.

In the accompanying drawings, Figure 1 is a perspective view of the table as arranged for 20 playing a game of pool; Fig. 2, a perspective view, showing the parts adjusted as when the table is not in use; Fig. 3, a transverse section of the table; and Figs. 4, 5, and 6 enlarged views of parts of the device.

A represents an ordinary sofa or lounge 25 body, upholstered as usual, and having feet a, but without the ordinary back. To the end frames of this lounge are pivoted, by means of bolts b, frames B, which are connected to the end bars of the frame D of a billiard or pool 30 table, that shown in the drawings being a pool-table, and having the cushions and pockets necessary in playing that game. When the table is turned up over the lounge, as in Fig. 1, a notched arm of each of the frames B is 35 adapted to a projecting stem, d, on one of the end frames of the lounge, and is secured thereto by tightening a nut, e, which, for convenience of manipulation, is made in the form of a wheel. The table is thus rigidly secured to the lounge- 40 frame, and the proper stability of said table is insured, the lounge-frame being accurately leveled by the adjusting-screws f, with which the feet of said lounge are provided.

A pool or billiard table constructed in the 45 ordinary way, however, is much too heavy and costly to be combined with a lounge or other article of furniture, as above set forth; hence I adopt a special method of making the table, with the view of obtaining at small cost a perfectly level and reliable playing-surface. This 50 construction is shown in Figs. 3 and 4, in which D represents the frame of the table, and E the

body of the same, which consists of boards accurately fitted together and secured against warping by suitable cleats on the back. This 55 body E is rabbeted at each edge, and is adapted to the rabbed inner edges of the frame D, being retained in place vertically by strips g secured to said frame. The upper edge of the body is made perfectly true and level with the 60 top of the frame D, and over both frame and body is tightly stretched a covering, m, of thick paper, which forms the backing for the cloth cover n. The paper cover is preferably dampened, and while expanded secured to the frame 65 D, before the application of the body E thereto, the latter not being applied until the paper is thoroughly dry and tightly stretched, so that the backing does not interfere with the drying 70 of the paper, and the dampness of the latter 7c has no tendency to cause the backing to warp. The body E forms a firm and uniform backing for the paper cover n, but is entirely disconnected therefrom, so that it is free to expand 75 and contract without affecting the smoothness or integrity of said paper covering. If the said body E is rigidly connected to the frame D at the edges, however, the unequal expansion and contraction of the two parts has a tendency to cause the body E to buckle, and thus interfere 80 with the truth of the table; hence I allow a space to intervene between the edges of the body E and the frame D, so as to permit independent expansion and contraction of either 85 part. (See Fig. 4.)

The pivot-bolts, b, for the end frames, B, of the table, have threaded portions, adapted to threaded openings in blocks s, secured to the end frames of the lounge, as shown in Fig. 5; and the securing-bolts d are passed through 90 openings in said end frames, and are secured thereto by nuts t, equal in thickness to the projecting portions of the blocks s. (See Fig. 6.)

The table has cushions, which may be constructed and applied in the usual manner; and 95 when intended for use in playing billiards instead of pool the breaks in the cushions where the pockets occur may be filled with short cushions constructed to fit said breaks.

I claim as my invention—

1. A portable game apparatus, in which a table adapted for pool or billiard playing is combined with a sofa or lounge body, and pivoted end frames, B, whereby the table may be 100

turned up over the lounge or sofa for playing, or turned down to form the back of said lounge or sofa, as set forth.

2. The combination of the lounge or sofa body, the table, the end frames, B, the pivot-bolts *b*, the bolts *d*, and securing-nuts *e*, as set forth.

3. The combination of the frame D of the table, the paper covering *n*, and the body E, forming a support for said covering *n*, but not secured thereto, as set forth.

4. The combination of the frame D and covering of the table with the body E, loosely fitted to the frame, so as to be free to expand and contract independently thereof, as set forth.

In testimony whereof I have signed my name to this specification in the presence of two subscribing witnesses.

JOSEPH SHERMAN.
